CLEAT CLEANER

William H. Williams, 704 Hobbs Drive,
Silver Spring, Md.
Filed Mar. 23, 1962, Ser. No. 182,066
2 Claims. (Cl. 15—215)

This invention relates to a device for cleaning cleats on athletic shoes and relates more particularly to a mat having a plurality of projections fixed to its upper surface for removing mud or the like from around and between the cleats of an athletic shoe.

Shoes with spiked cleats are commonly used in many sports because the players require stability and sure-footedness. In golf and baseball the cleated shoes enable the player to maintain a correct stance and provide the support necessary for the accuracy and power used in hitting the ball. Other athletes, such as football and soccer players, must be able to stop suddenly and change direction quickly, and cleated shoes are necessary for such dexterity.

Cleated shoes are only effective in providing sure-footedness if the cleats are free to dig into the dirt or other soft surface on which the sport is played. Difficulty is encountered when the dirt cakes about and between the cleats. When this occurs the cleats cannot function to adequately dig into the playing surface and the player will be almost as poorly equipped as if he were wearing smooth-soled shoes or sneakers. Cleats have a special tendency towards becoming less efficient when the ground is wet, since mud has a great tendency to cling. Many athletic courses are continuously watered for maintenance purposes and many sports are played regardless of the weather, so mud is often found to be present on and around playing fields.

The loss of stability caused by mud, dirt, and other foreign material clinging around and between cleats on athletic shoes leads to loss of power and accuracy and is the reason for many slips and falls which oftentimes cause injury to the player. Athletes try to overcome this problem by tapping their shoes with a baseball bat, a golf club, or some other handy implement. This expedient rarely effects good cleaning, especially when mud or a sticky clay is caked on the shoes, and such a procedure can be damaging to the player's equipment. Small hand devices such as brushes or scrapers have been used but it is difficult to adequately clean with such means unless the player removes his shoes, a procedure which is obviously impractical in most sports.

It is an object of this invention to provide a cleat cleaner free from the foregoing and other disadvantages.

It is a further object of the instant invention to provide a device which will effectively clean dirt, mud or other foreign material from between and around cleats, spikes or other projections on the bottom of athletic shoes and the like.

A further object of this invention is to provide a mat which may be placed at convenient locations around an athletic field or course so that players may quickly and effectively free the cleats on their shoes from foreign material clinging thereto.

Another object of the instant invention is the provision of a mat having a plurality of projections with various novel shapes designed to cut into and scrape dirt or mud from around and between cleats on the sole of an athletic shoe.

Other objects and advantages of this invention will be apparent from the following detailed description and will be particularly pointed out in the appended claims.

In the drawings, wherein preferred embodiments of the instant invention are shown,

2

FIGURE 1 is a plan view of a cleat cleaner in accordance with this invention;

FIGURE 2 is a partial cross-sectional view on line 2—2 in FIGURE 1 in the direction of the arrows;

5 FIGURE 3 is a plan view of a portion of a further embodiment of a cleat cleaner;

FIGURE 4 is a cross-sectional view on line 4—4 in FIGURE 3 in the direction of the arrows;

10 FIGURE 5 is a plan view of a portion of another embodiment of a cleat cleaner in accordance with this invention;

FIGURE 6 is a partial cross-sectional view on line 6—6 of FIGURE 5 in the direction of the arrows;

15 FIGURE 7 is a plan view of a portion of a further embodiment of the cleat cleaner of the instant invention;

FIGURE 8 is a side view of the embodiment of FIGURE 7 on line 8—8 in the direction of the arrows;

20 FIGURE 9 is a side view of a modification of the cleat cleaner in accordance with the instant invention;

FIGURE 10 is a plan view of a portion of a cleat cleaner showing one of the projections according to another embodiment of this invention, partly in section;

25 FIGURE 11 is a side view, partly in section, of the embodiment of FIGURE 10.

Like reference numerals refer to like parts throughout the several views of the drawings.

Referring now to the drawings for a detailed description of the instant invention, and particularly to FIGURES 1 and 2, reference numeral 2 designates a mat having a

30 lower surface 4 and an upper surface 6. Fixed to the upper surface 6 are a plurality of upwardly extending projections 8. In the embodiment of FIGURES 1 and 2, each of the projections 8 is in the form of a solid right- pyramid having four inwardly and upwardly sloping sides 10 and a V-shaped gouge or groove 11 cut into the top thereof. The projections 8 are placed on the mat 2 in staggered relationship, as will be clearly seen from FIGURE 1. The space 12 between individual projections depends on the particular sport for which the cleat cleaner is to be adapted and will be approximately equal to the diameter of the cleats used. The height 13 of the projections 8 will likewise depend on the size of the cleats used in the particular sport and will vary from slightly less to slightly in excess of the overall height of the cleat.

35 The projections 8 can be made of any of a variety of materials such as metal, hard rubber, a relatively rigid plastic material, or metal chips dispersed in rubber or plastic. It is preferable to make the projections 8 of a relatively rigid, but slightly flexible material which will 40 act to scrape the sides of the cleats and the sole of the shoe between the cleats. If the projections 8 are flexible it is advantageous to have their height 13 slightly longer than the cleats on the shoes to be cleaned so that the V-shaped gouge 11 can act to scrape the shoe sole. If 45 a rigid material such as metal is used, the height 13 of the projections 8 must be slightly shorter or equal to the height of the cleats in order not to hurt the foot of the wearer. Apertures 14 may be provided in the mat 2 to allow suitable nails or the like to be inserted therethrough to hold the mat 2 stationary with respect to the ground. A chamfer 20 may be provided around the 50 periphery of the mat 2 for safety reasons.

55 The cleat cleaner described above is placed at various convenient locations around the athletic field or course such as by each tee on a golf course, by home plate on a baseball field, or on the sidelines of a football field or soccer field. The player utilizes the cleat cleaner by scraping his shoes over the surface of the mat so that the projections 8 rub against the sides of the cleats and the sole of the shoe between the cleats.

60 65 70 Various modifications of the above concept can be

made for special applications or particular effects. FIGURES 3 and 4 show an embodiment having a plurality of elongated conical projections 22 fixed to the mat 2. The projections 22 are slightly flexible and act like a brush to clean the cleats when the shoes are scraped over the mat. Another feature of this mat is the lower surface 24 which is roughened in order to prevent the mat from slipping in use. This expedient can be relied on by itself or used in conjunction with nail-receiving apertures such as 14 shown in the embodiment of FIGURES 1 and 2.

In FIGURES 5 to 8, a cleat cleaner is shown having projections 26 with a plurality of flexible vanes 28 extending outwardly therefrom which act to scrape the surface of a cleat being passed between the projections. The number of vanes 28 and their dimensions and placement on the projections 26 may be varied. In FIGURES 5 and 6 the projections 26 are in the shape of a frustum of a right-pyramid and have four flexible vanes 28, each shorter than the height 29 of the projections 26. Alternate vanes 28 in this embodiment are in spaced vertical planes to insure scraping action along the full length of the cleat. FIGURES 7 and 8 show flexible vanes 28' which run the full length of the projections 26' and taper from the bottom to the top. The projections 26 may be fixed to the mat 2 by integrally molding a central supporting member 30 made of metal or some other rigid material inside a flexible outer material 32. Nails 34 or the like can also be integrally molded into the mat 2 so that their pointed ends 36 will project from the bottom surface thereof. This will maintain the cleat cleaner stationary by merely pressing it to the ground. An upstanding side wall 38 may also be provided around the periphery of the mat 2 to prevent accidental stepping on the projections 26, especially if an internal rigid supporting member such as 30 is centrally located in each projection. The height of the side wall 38 will be preferably approximately equal to the height 29 of the projections 26. Only by purposely stepping down into the cleat cleaner over the side wall 38 will anyone come into contact with the projections 26.

Each of the projections may be equal in height and perpendicular to the mat 2 as in the above-described embodiments, or the axis 40 of each projection 42 may be slanted as shown in FIGURE 9. With such an arrangement, the shoe would be scraped from the right to the left so that the slanted projections would cut into and push off any mud clinging between the cleats. The projections 42 may be varied in length, such as shown at 44, to scrape different portions of the cleats and the shoe 50 sole at the same time.

FIGURES 10 and 11 show a further embodiment of the novel cleat cleaner of the instant invention. A hollow projection 46 is formed from a plurality of rigid side walls 48 having cutting edges 50 on their upper surfaces and a coating of flexible material 52 extending outwardly therefrom to form flexible vanes 54. The player steps straight down on a cleat cleaner of this design and the cutting edges 50 act in the manner of a cookie cutter to cut the mud from between and around the cleats and hold the same in the cavity 56 after the shoe is removed from the device. The flexible vanes 54 will assist in brushing dirt and mud from the surfaces of the cleats while the shoe is moved back and forth after first stepping onto the mat. The projections 46 are

5 hollow and taper from the bottom to the top to allow the dirt to fall into the cavity 56 between the walls 48. The mat 2 may be cut through beneath each projection, as shown at 58, so that, on picking up the cleat cleaner, the accumulated dirt and mud will be easily removed from the device. Any conventional manner of fixing the projections 46 to the mat 2 and the coating 52 to the walls 48 may be employed. For example, the mat 2 and the coating 52 may be integrally molded around the walls 48, or the coating 52 could be fixed to the walls 48 in the form of a laminate by an adhesive material.

10 It is to be understood that many of the novel features shown above with regard to particular embodiments are applicable to any of the embodiments disclosed. For example, any of the mats 2 may have nail receiving holes such as shown at 14 in FIGURES 1 and 2, a rough lower surface such as 24 in FIGURE 4, or partially embedded nails such as 34 in FIGURES 5 and 6. Moreover, the concept of having a central supporting member such as 30 in FIGURE 6, or slanted projections of different lengths such as shown in FIGURE 9, could easily be applied to the other disclosed embodiments. Similarly, the hollow cutting projections 46 of FIGURES 10 and 11 could have shorter staggered flexible vanes such as those shown at 28 in FIGURES 5 and 6, or no vanes at all.

15 20 25 It is to be understood that the foregoing detailed description is given merely by way of illustration and that many variations may be made therein without departing from the spirit of this invention as set forth in the claims.

30 What is hereby claimed and is desired to be secured by Letters Patent is:

35 1. A cleat cleaner comprising a mat having an upper and a lower surface, a plurality of projections fixed to said upper surface, each projection having a central axis, a top in a plane remote from said mat and a bottom adjacent the upper surface of said mat, said projections being spaced on said mat in staggered relationship to each other, the central axis of each projection being perpendicular to said mat and each of said projections having a plurality of outwardly directed flexible vane members evenly spaced around said central axis.

40 45 2. A cleat cleaner in accordance with claim 1, where- in said vane members extend the full length of each of said projections, and said vane members progressively decrease in width from the bottom to the top of said projections.
